(57) **CLAIM**

The ornamental design for a cone unit for tire bead collapsing assembly in a tire bead winding assembly, as shown and described.

DESCRIPTION

FIG. 1 is a perspective view of a new design of a cone unit for tire bead collapsing assembly in a tire bead winding assembly, with elements of the collapsing unit shown in phantom lines for illustrative and environmental purposes only;

FIG. 2 is a perspective view of the cone unit;

FIG. 3 is a side elevational view thereof, the other side elevation being a mirror image thereof;

FIG. 4 is a top plan view thereof, the bottom plan view being a mirror image thereof;

FIG. 5 is a rear elevation view thereof; and,

FIG. 6 is a front elevation view thereof.
